(57) **CLAIM**

The ornamental design for a grille surround profile, as shown and described.

DESCRIPTION

FIG. 1 is a perspective view of a grille surround profile showing our new design;

FIG. 2 is a front view of the grille surround profile shown in FIG. 1;

FIG. 3 is a top view of the grille surround profile shown in FIG. 1;

FIG. 4 is a left side view of the grille surround profile shown in FIG. 1; and,

FIG. 5 is a right side view of the grille surround profile shown in FIG. 1.

The broken lines shown in the figures represent portions of the grille surround profile that form no part of the claimed design. The dash-dot broken lines define the boundaries of the claim and form no part of the claimed design.
